CLAIM

The ornamental design for a sports bottle cap with spout and finger loop for stainless steel bottle, as shown.

DESCRIPTION

FIG. 1 is an exploded perspective view of the aligned parts of the sports bottle cap with spout and finger loop for stainless steel bottle;

FIG. 2 is a front elevational view of the sports bottle with cap and finger loop for stainless steel bottle shown without the cap and attached finger loop for the clarity of illustration;

FIG. 3 is a back elevational view thereof;

FIG. 4 is a side elevational view thereof;

FIG. 5 is a top plan view thereof;

FIG. 6 is a bottom plan view thereof; and,

FIG. 7 is a perspective view of the sports bottle cap with spout and finger loop for stainless steel bottle shown mounted on a phantom stainless steel bottle.

The broken lines shown in FIG. 7 represent portions of the design that form no part of the claim.
